UNITED STATES PATENT OFFICE.

ELEUTHERE SIX, OF MILTON, PENNSYLVANIA, ASSIGNOR TO SUSQUEHANNA SILK MILLS, OF NEW YORK, N. Y., A CORPORATION OF NEW YORK.

SELF-THREADING THREAD-TENSION DEVICE FOR SHUTTLES.

Application filed October 2, 1921. Serial No. 505,051.

To all whom it may concern:

Be it known that I, ELEUTHERE Six, a subject of the King of Belgium, residing at Milton, in the county of Northumberland and State of Pennsylvania, have invented certain new and useful Improvements in Self-Threading Thread-Tension Devices for Shuttles, of which the following is a specification, reference being had therein to the accompanying drawings.

This invention relates to a self-threading thread tension device for shuttles, and the object of the invention is the construction of a simple and efficient tension device for automatic shuttles, whereby the thread from the bobbin will fall into both the threader block and the tension device as soon as the pick of the shuttle is started.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a fragmentary, perspective view of a shuttle body, showing my tension device applied thereto.

Figure 2 is a sectional view taken on line 2—2, Fig. 1, and looking in the direction of the arrows.

Figure 3 is a perspective view of two of the elements or "blocks" employed in the construction of my tension device.

Figure 4 is a perspective view of one of the elements or "blocks" of another embodiment of the present invention, while

Figure 5 is a top plan view of the same. Figure 6 is a perspective view of still another embodiment of the present invention.

Referring to the drawings by numerals, 1 designates a shuttle-body, 2 the bobbin therein, and 3 is the threader block.

In the preferred embodiment of my invention (Figs. 1 to 3), I employ two elements or "blocks" 4 and 5; these blocks are preferably rectangular in shape and each block, near its lower end, is provided with a pair of transverse, horizontal apertures 6, through which a pair of pins or rods 7 extend; these rods extend transversely through the shuttle-body 1, near its bottom, and preferably between the bobbin 2 and the

threader block 3, Fig. 1. The upper, inner face of each member or block 5 is beveled at 8 to allow the thread 9, from the bobbin 2, to readily fall in between the blocks 4 and 5. Block 4 is preferably fastened by any suitable means, such as glue, against the shuttle-body, whereas block 5 is free to slide laterally away from block 4 upon the rods 7. A spring-receiving socket 10 is formed in the block 5 and a spring 11 is seated at one end in the socket 10; the other end of the spring bears against the shuttle-body 1, and this spring normally holds block 5 against block 4.

I use the term "blocks" in designating the elements 4 and 5 in a broad sense, as these "blocks" may be styled "jaws," or "clamping elements," or the like, and I do not limit myself to any specific kind of material in constructing the "blocks," although these "blocks" are preferably formed from a fibre compound.

Upon referring to Figs 1 and 2, it will be noted that the standard threaded block has a longitudinal slot 12 extending throughout its length, and the tension device is also provided with a longitudinally-extending slot 13 extending throughout its length; the two slots 12 and 13 register and open free upon the upper face of the shuttle-body, whereby the thread 9, from the bobbin, will fall into both automatically as soon as the pick of the shuttle has started. In the embodiment shown in Figs. 4 and 5, I have illustrated a structure what might be termed a "washboard" tension device, inasmuch as both the blocks 4 and 5 are vertically corrugated at 14; the corrugations have rounded outer surfaces and taper toward their upper ends to merge in the flat inner upper surfaces of the blocks.

In the embodiment shown in Fig. 6, the thread 9 passes between substantially looped wire frames 15, extending inwardly from the inner faces of the bodies 16 that support these wire frames 15 upon the rods 7. It will be noted that the frames are spaced apart on each block or body 16 and the frames of one body are staggered with respect to the frames of the other body, so that the frames of one body will extend between the frames of the other body, whereby the thread will be firmly gripped.

While I have described the preferred embodiments of my invention, and have illus-

trated the same in the accompanying drawings, certain minor changes or alterations may appear to one skilled in the art to which this invention relates, during the extensive manufacture of the same, and I therefore, reserve the right to make such alterations or changes as shall fairly fall within the scope of the appended claims.

What I claim is:

- 10 1. In a device of the character described, the combination of a shuttle body, a pair of substantially rectangular blocks positioned in said body, means for slidably supporting said blocks, means for urging said blocks together, the inner lower surfaces of said blocks being corrugated vertically, the corrugations having rounded surfaces and tapering toward their upper portions so as to finally merge in the flat inner upper surfaces of the blocks.
- 15
- 20

2. In a device of the class described, the combination of a shuttle body, a pair of substantially rectangular blocks positioned in said body, a pair of parallel, horizontal rods in the lower part of the body and extending through the lower portions of the blocks, one block fixedly secured against movement upon said rods and the other block being slidably mounted on the rods, said slidably mounted block provided with a spring seat in its outer surface, said body provided contiguous to said slidably mounted block with a straight wall, a coil spring seated at one end in said spring seat and bearing at its other end against said straight wall, and said spring being held in an operative position by said spring seat.

In testimony whereof I hereto affix my signature.

ELEUTHERE SIX.
